DESIGN FOR A GLASS TUMBLER

George Dougherty, Morgantown, W. Va., assignor to Morgantown Glass Works, Morgantown,
W. Va., a corporation of West Virginia

Application July 3, 1935, Serial No. 57,517

Term of patent 14 years

To all whom it may concern:

Be it known that I, George Dougherty, a citizen of the United States, residing at Morgantown, in the county of Monongalia and State of West Virginia, have invented a new, original, and ornamental Design for a Glass Tumbler, of which the following is a specification, reference being had to the accompanying drawing, forming part thereof.

Figure 1 is a longitudinal sectional view of the tumbler, showing my design, and Figure 2 is an elevational view thereof.

I claim:

The ornamental design for a glass tumbler, as shown and described.

GEORGE DOUGHERTY.
